CLAIM

The ornamental design for a shower drain hair-trap, substantially as shown.

DESCRIPTION

FIG. 1 is a perspective view taken from the top, front and left side of a shower drain hair-trap, showing my new design;

FIG. 2 is a rear elevational view thereof;

FIG. 3 is a right side elevational view thereof;

FIG. 4 is a left side elevational view thereof;

FIG. 5 is a bottom plan view thereof; and

FIG. 6 is a top plan view thereof.
